CLAIM

The ornamental design for a retail furnishings group, as shown and described.

DESCRIPTION

FIG. 1 is a front perspective view of a retail furnishings group showing the claimed design; FIG. 2 is a left side view thereof; FIG. 3 is a right side view thereof; FIG. 4 is a front view thereof; FIG. 5 is a rear view thereof; and, FIG. 6 is a top view thereof.

(Continued)

The dashed broken lines in the figures show portions of the retail furnishings group that form no part of the claimed design.

The dot-dash broken lines in the figures show boundaries of the claimed design.

1 Claim, 6 Drawing Sheets
